UNITED STATES PATENT OFFICE

JESSE O. THOMSON AND FREDERICK W. THOMSON, OF PHILADELPHIA, PENNSYLVANIA, ASSIGNORS TO WILLIAM THOMSON, INC., OF PHILADELPHIA, PENNSYLVANIA, A CORPORATION OF PENNSYLVANIA

GAS RANGE

Application filed September 22, 1928. Serial No. 307,511.

Our invention relates to a new and useful improvement in gas ranges or other ranges using fluid fuel.

It is the object of our invention to provide a novel combination of broiling oven and griddle plate in such a manner that a single set of burners may be employed for both and so that the heat normally wasted in a broiler oven is utilized for the griddle plate, and so as, moreover, to provide a better heat reflecting surface on the top of the broiling oven, thereby to increase the efficiency of the latter by more evenly distributing the heat therein.

With the above ends in view we provide a broiling oven with a range, the top wall of which instead of being of the usual construction, is in the form of a removable, relatively thick metallic griddle plate.

For the purpose of illustrating our invention we have shown in the accompanying drawings one form thereof which is at present preferred by us, since the same has been found in practice to give satisfactory and reliable results, although it is to be understood that the various instrumentalities of which our invention consists can be variously arranged and organized and that our invention is not limited to the precise arrangement and organization of the instrumentalities as herein shown and described.

Figure 1 represents a perspective view of a four burner range embodying our invention.

Figure 2 represents a section on line 2-2 of Figure 1.

Figure 3 represents a perspective view of a six burner range embodying our invention.

Figure 4 represents a section on line 4-4 of Figure 3.

The gas range embodying our invention is designated generally by the numeral 5 and is provided with four burners 6 in the usual manner supplied by a common supply line 7.

The broiling oven is designated generally by the numeral 8 and consists of a chamber extending substantially across the depth of the range immediately below the upper surface thereof and surrounded by the walls 9 and 10 and a bottom 11.

Suitable guide supports 12 are provided

along the walls 9 and 10 at various heights for the purpose of supporting the shelf 13 at the various levels.

From the gas supply line 7 a pair of burner pipes 14 and 15 are extended longitudinally within the chamber 8 and spaced a suitable distance from each other.

The top of the chamber 8 is formed of a relatively thick metallic plate 16, preferably of aluminum, which is supported in the top 17 of the range by the recessed shoulders or flanges 18, as indicated particularly in Figure 2. The top of the plate 16 is then flush with the top of the range.

The griddle plate 16 may be provided with a pair of handles 19, by means of which it may be readily removed for the purposes of cleaning or otherwise. A relatively small drip channel 20 is provided near the border of the griddle plate 16 for the purpose of collecting any drainings or drippings from the griddle plate.

The broiling pan 21 is supported upon a shelf 13 immediately below the burners 14 which are thereby positioned intermediate the broiling pan and the griddle plate.

The heat of the flame from the burners 14 and 15 is thus transmitted to the broiling pan both directly and by reflection from the griddle plate 16 which reflects the heat downwardly. In so reflecting the heat downwardly the griddle plate is maintained at a constant temperature suitable for making wheat cakes and the like.

A hole 22 is also provided through the griddle plate at any suitable point, and communicating with the drip channel 20 so as to convey the draining or drippings from the griddle plate into the pan 21 below.

In Figures 3 and 4 we have illustrated another embodiment of our invention as applied to a six burner range, in which the griddle plate 16 is raised above the top 23 of the range so as to allow for the usual ovens 24 and 25 as well as the broiling oven 26.

In this instance, the broiling oven chamber 26 is raised somewhat by the upward extension of the walls 9 and 10 which in turn carry the recessed flanges 18 at the top for the reception of the griddle plate 16.

We are aware that the invention may be embodied in other specific forms without departing from the spirit or essential attributes thereof, and we therefore desire the present embodiment to be considered in all respects as illustrative and not restrictive, reference being had to the appended claims rather than to the foregoing description to indicate the scope of the invention.

10 Having thus described our invention what we claim as new and desire to secure by Letters Patent, is:—

15 1. A gas range having an upward extension at one end thereof and having arranged above said upward extension a laterally extended elongated opening provided with a recessed portion, a flat griddle plate removably fitted to said recessed portion, a peripherally arranged drip channel arranged in the flat top 20 of said griddle plate, there being an aperture through said griddle plate and in communication with said channel for deflecting drip to said upward extension, a gas supply pipe at the range front, and burners connected with 25 said supply pipe and extended laterally in spaced relation through said oven beneath said griddle plate.

30 2. A gas range having an upward extension at one end thereof and having arranged above said upward extension a laterally extended elongated opening provided with a recessed portion, a flat griddle plate removably fitted to said recessed portion, a peripherally arranged drip channel arranged in the flat top 35 of said griddle plate, there being an aperture through said griddle plate and in communication with said channel for deflecting drip to said oven, a gas supply pipe at the range front, burners connected with said supply 40 pipe and extended laterally in spaced relation through said upward extension beneath said griddle plate, and handles arranged at each end of said griddle plate.

JESSE O. THOMSON.
